No. 834,402.

PATENTED OCT. 30, 1906.

J. H. PEICK.
BENCH CLAMP.
APPLICATION FILED NOV. 18, 1905.

UNITED STATES PATENT OFFICE.

JOHAN HENRIKSEN PEICK, OF BINGHAMTON, NEW YORK.

BENCH-CLAMP.

No. 834,402.

Specification of Letters Patent.

Patented Oct. 30, 1906.

Application filed November 18, 1905. Serial No. 288,044.

To all whom it may concern:

Be it known that I, JOHAN HENRIKSEN PEICK, a subject of the King of Denmark, and a resident of Binghamton, in the county 5 of Broome and State of New York, have invented certain new and useful Improvements in Bench-Clamps, of which the following is a specification, reference being had to the accompanying drawings.

10 My invention relates to improvements in clamps for holding wood or other material upon a bench or like support during the time that it is being worked upon by the artisan; and the object of my invention is to produce 15 a clamp of this kind which shall be simple in construction, cheap in manufacture, and efficient in operation.

In the drawings illustrating the principle of my invention, and the best mode now 20 known to me of applying that principle, Figure 1 is a side elevation of my new clamp, and Fig. 2 is a front elevation of the same.

The bench *a* is formed with a hole through which passes the rod *b*, from the upper end of 25 which extends a curved arm *c*, pivotally mounted in which is the clamp-lever *d*. Mounted free to swing upon the upper end of the rod *b* is the handle-bar *e*, the lower part of which is slotted to receive the pins *f*, which 30 project from the upper end of the clamp-lever *d*. The handle-bar *e* carries a roller *g*, (see Fig. 2,) which is adapted to bear against the under surface of the upper end of the clamp-lever *d*, and which, being given a cam 35 action by said handle-bar, may be called a "cam-roller."

The operation of the clamp will be readily understood from the foregoing description and an inspection of Fig. 1, in which the released position of the clamp is shown in dotted lines. When the handle-bar *e* is thrown

to the left in Fig. 1, the curved wall *h* bears upon the pins *f*, and thereby depresses the upper end of the clamp-lever and raises the lower end thereof from the work *i*. When 45 the handle-bar *e* is thrown to the right in Fig. 1, the roller *g* rides up under the lower cam-surface of the upper end of the clamp-lever *d*, and thereby raises the said upper end and presses the free end of the clamp-lever *d* 50 against the work, as shown in the full lines in Fig. 1.

What I claim is—

1. A bench-clamp comprising the combination of a supporting-rod formed with an 55 arm; a handle-bar mounted free to swing upon said rod and provided with a roller, the lower end of said handle-bar being slotted; and a clamp-lever mounted in said arm and having one end adapted to engage with said 60 roller, said end being provided with pins which engage in the slots in the lower end of said handle-bar.

2. A bench-clamp comprising the combination of a support; an operating handle-bar 65 mounted therein, formed with a cam-slot and provided with a cam-roller; and a clamp-lever mounted in said support and formed with a cam-surface against which rubs said cam-roller; one end of said clamp-lever being 70 operated by one wall of said cam-slot; one movement of said handle-bar causing the wall of said cam-slot to swing said clamp-lever in one direction and the reverse movement of said handle-bar causing said cam- 75 roller to swing said clamp-lever in the opposite direction.

JOHAN HENRIKSEN PEICK.
